UNITED STATES PATENT OFFICE.

WILLIAM G. ABBOTT, JR., OF PHILADELPHIA, PENNSYLVANIA.

GAS-ENGINE.

961,059.

Specification of Letters Patent.

Patented June 7, 1910.

Application filed December 30, 1905. Serial No. 293,992.

To all whom it may concern:

Be it known that I, WILLIAM G. ABBOTT, Jr., a citizen of the United States, and a resident of the city and county of Philadelphia, State of Pennsylvania, have invented certain new and useful Improvements in Gas-Engines, of which the following is a full, clear, and exact description.

My invention relates to the use of volatilized hydrocarbons and the mixture of the same with air to produce combustion, and the use of the resulting energy in doing work.

One object of my invention is to utilize the products of said combustion in certain motors, having details of construction essential to the utilization of said hydrocarbons in a manner which I will hereinafter describe.

A further object of my invention is to volatilize or vaporize a hydrocarbon, and to introduce the said vapor of gas into the cylinder of a four cycle hydrocarbon engine. At the time of the introduction of the vapor into the cylinder, its temperature is such that the mean temperature of the mixture will be high enough to cause a kindling or burning of the same. As is well known in this art, the combustion is usually effected by the introduction into a combustion chamber of a hydrocarbon oil, gas or vapor in the presence of air usually compressed. This mixture of gas and air is called the charge and the combustion of the same may be caused at predetermined times by bringing it into contact with some igniting means, such as an electric spark or flame. Some charges, however, may be burned without the application of any ignition means. This is true in cases where the mean temperature of the mixture of the hydrocarbon and air is equal to or exceeds the kindling temperature of the former. This kindling temperature in the mixture is usually obtained by compressing the charge or compressing the air before mixing or heating the charge or heating the air before mixing in some other manner. In my invention, however, I obtain the kindling temperature for the charge by heating and compressing the vapor before the same is introduced into the combustion chamber or into the presence of the air, thus enabling the use of air at a much lower temperature and degree of compression than that usually employed in four cycle engines.

Further objects of my invention will appear hereinafter.

In the accompanying drawings, Figure 1 is a fragmentary longitudinal sectional view 60 of a compound four-cycle engine constructed in accordance with this invention; Fig. 2 an elevation partly in section of details of the same; Fig. 3 an enlarged horizontal fragmentary section of a portion of the 65 same; and Fig. 4 a fragmentary longitudinal section of a modified form of this invention.

Referring to Fig. 1, one embodiment of this invention comprises two high pressure 70 water jacketed four cycle engine cylinders 1-1, having therein pistons 2-2 and piston rods 3-3. Behind the pistons are located the inwardly opening poppet valves 4-4. The lower cylinder heads may be bolted on 75 and the piston rods reciprocate through stuffing boxes constructed in the usual manner. Attached to the upper sides of the cylinders are the vaporizers 5-5, the details of which will be hereinafter described. 80 These vaporizers have communication with the working end of the cylinders through the passages 6-6, the said passages being opened and closed by proper valve action.

Screwed into the upper heads of the cylinders are the valve chambers, each of which consists of a cylindrical portion 7, having orifices therein 8 and 9, and the annularly channeled rings 10 and 11 driven down over said cylinder, to have their channels coincide 90 with the orifices 8 and 9. A valve plug 12 reciprocates up and down in each cylinder to open and close the orifice leading to said channels. This plug contains longitudinal channels or passages 13 and a central passage 95 for the reciprocating valve stem 14, which opens and closes the poppet valve 15 at the bottom of the valve chamber. The top of each chamber is closed by a head 16, which is screwed on to the exterior of the 100 cylindrical portion. This head contains stuffing boxes for the reciprocating valve stem 14 and for the plunger rod which reciprocates the valve plug 12.

A low pressure single acting expansion 105 cylinder 17 is provided, having a piston 18 therein and a piston rod operated by the exhaust gases of the other two cylinders. In the head of the cylinder 17 is screwed a valve chamber similar to that of the cylinders 1 and 2. This valve chamber consists of a cylindrical portion 20, having orifices

therein 21 and 22. Over the said orifices on the outside of the cylindrical portion are driven or screwed down annular channeled rings 23 and 24, the channels in the said 5 rings coinciding with the orifices in the cylindrical portion. A piston like valve plug 25, is reciprocated up and down in this valve chamber by means of the plunger rod 26, to alternately open and close said orifices.

10 A compressed air tank or chamber 27 is provided, leading from which are two pipes 28 containing cocks 29. In the upper annular channeled rings of the valve chambers on the cylinders 1—1 are ports, out of which 15 lead the pipes 30—30, which pipes connect up said ports with the compressed air tank 27. On each end of the compressed air tank is a dome 31, into one of which leads an exhaust pipe 32 from a port in the lower 20 annular channeled ring of the valve chamber on the low pressure cylinder 17. The domes 31—31 are connected up with each other by means of a series of pipes 33, running longitudinally through the compressed 25 air tank. The pipes 34—34 connect up ports in the lower annular channeled rings on the cylinders 1—1 with the ports of the upper annular channeled ring on the cylinder 17.

Each of the vaporizers 5 comprises, as 30 shown in Fig. 3, a vaporizing chamber 35, having a passage 36 through the middle thereof, and an opening in each corner closed by screw plugs 37, which may be removed in order to gain access to the vaporizer for 35 cleaning or other purposes. The said vaporizer may be made out of a single casting bored in four directions, to form the passage around the central portion. A tube 38 screwed into the cylinder 1 supports the said 40 vaporizer, the vaporizer being slid over the tube until close against the cylinder, and secured thereto by a screw plug 39, in which is located the packing box for the needle 40, which extends axially through the tube 38 and is adapted to close the valve seat 41. This valve seat opens into the passage 6, 45 which leads into the working end of the cylinder.

A modified form of the valve chambers 50 illustrated in Fig. 1 is shown in Fig. 4, in which the valve chamber 43 is provided with ports 44 and 45 and with an opening 46 leading into the cylinder 1, which may be closed by the poppet 47. The ports 44 and 55 45 are alternately opened and closed by the piston like valve plug 48, which reciprocates in the same manner as the valve plugs 12—12 previously described.

Referring to Fig. 2, the vaporizer 5 illustrated in detail in Fig. 3, is provided with a pipe 3' leading therefrom to the oil tank 1'. Oil is supplied to the vaporizer by means of a pump 4' connected up with the pipe 3', and actuated in any manner, as for instance by 65 an eccentric 50 upon the crank shaft or other

suitable shaft 50' driven by the engine, and a suitable eccentric strap 51 carried by the eccentric 50 and carrying an eccentric rod 51' pivoted to one end of a rocker 52, the other end of which is connected by a link 53 to the piston rod 54 of the pump. This pump 70 may be arranged to furnish predetermined amounts to the vaporizer. For keeping up a constant pressure in the vaporizer a pressure regulator 6' and pressure dome 7' are 75 located in the pipe 3' between the vaporizer and the pump. The pressure regulator communicates with the by-pass 5', which carries the oil back to the other side of the pump. The needle valve 40 of the vaporizer 80 is positively operated by a rocker arm 55 in the form of a bell-crank pivoted at 56, and one end of which engages with the outer end of the needle, and the other end of which carries a cam roller or follower 57 85 which engages against a cam 58 adjustably mounted upon a shaft 59 rotated by the engine as usual. The cam 58 may be adjusted in any position upon its shaft 59 by means of a set screw 60 and by this adjustment the 90 needle or fuel valve 40 may be operated at predetermined intervals.

In the operation of this engine, any volatile oil may be used, but I prefer those of the heavier type, such as kerosene, and for the 95 purpose of this description will use the word kerosene, but any other suitable volatile oil may be used in its place. As heretofore described, the oil is stored in the tank 1', and is conveyed in the usual manner to the vaporizer 5. In this vaporizer heat is applied to the walls of the central passage 36. This heat may be furnished by the exhaust of the engine or by any other suitable means, such as a flame, from a burner 65 supplied with 100 fuel from the interior of the vaporizer by means of a pipe 66, having a valve 67. The presence of the heat will cause the oil to volatilize rapidly, and the chamber being closed, the accumulated vapor becomes 105 compressed. This pressure is kept at a certain degree by means of the pressure regulator 6'. The temperature of the gas or vapor, both by virtue of the application of heat and its own compression, is thus raised 110 above its kindling temperature, that is, above a temperature at which it would immediately combine with air to cause combustion.

Referring to Fig. 1, the engine may be started by turning the same over to open the 115 poppet valve 15, thus admitting compressed air from the tank 27 or other source, the air having been first compressed if necessary by turning over the engine by hand, or in any other similar manner, by the way of the 120 pipe 30, port 9 and channels 12, into the lower end of the valve chamber and through the opening therein into the cylinder. The valves connected with the vapor chambers 125 being cut off, and also the rear end of the 130

high pressure cylinders being open to the atmosphere by raising the poppets, or by other suitable means, and the cocks 29 and 29 being closed, the engine will now act like a compressed air engine, the air expanding against the piston 2 of the left hand cylinder, and the piston, on its return stroke, forcing the partially expanded air out by the poppet 15 through the exhaust pipe 34, and into the low pressure cylinder 17.

On the next forward stroke of the piston 2 in the left hand cylinder this operation is repeated. After the engine is thus started, the compressor sides of the pistons may be closed, and the cocks 29 and 29 may be opened and the valves in the vaporizer put in operation, in order that the regular cycle of the engine may be carried out. Of course, it is understood that the reciprocating valves 20 in the valve chambers and vaporizers, together with the piston rods, are connected up with suitable eccentrics and cranks on the crank shaft, the construction and operation of which is old in the art and, therefore, 25 needs no illustration. It may be said, however, that the cranks which operate the pistons of the high pressure cylinders work together in such a manner as to cause the pistons 2—2 to have a parallel stroke, and the 30 crank of the low pressure cylinder is in such a case opposite those of the high pressure cylinders, thus causing the piston 18 to have an alternate stroke with the pistons 2—2. The strokes of the high pressure pistons, 35 however, are not the same, but are one half cycle apart; that is, the outward working stroke in one cylinder takes place during the period of the idle stroke in the other cylinder. This causes them to exhaust alternately, the said exhausts making each outward stroke of the low pressure cylinder a working stroke.

Assuming that the engine has been started and that the piston 2 in the right hand cylinder is at the end of its forward stroke, as indicated in Fig. 1, and that a charge of compressed air has been admitted in the cylinder in the rear of the piston, the said piston begins its return stroke, compressing the air, 50 which air is heated by its own compression. At or about the end of the return stroke the valve in the vaporizer is opened, and the hot vapor is forced into the cylinder through the narrow passage 6 by virtue of its own compression, which is much higher than that of the compressed air.

As heretofore stated, the compressed air is at a lower temperature than that of the injected vapor, and on their mixing in front 55 of the piston their mean temperature will be equal to or above the kindling temperature of the vapor, which will instantly take fire, and combustion thus may be carried on while the mixture is expanding until the 65 piston 2 reaches the end of its return stroke,

or the combustion may be cut off at any period during said stroke by adjusting the valve gear in a well known manner to close said valve in the vapor chamber at a pre-determined time.

While the piston 2 in the right hand cylinder is thus being forced down on its forward stroke by the expanding of the burning gases, the piston 2 of the left hand cylinder is drawing in a fresh charge of compressed air from the tank 27 through the poppet valve 15.

On the third and return stroke of the piston 2 of the right hand cylinder the poppet valve 15 opens, and the burned gases are 80 expelled through the pipe 34 into the low pressure engine 17, where they act expansively in a manner similar to that of a steam engine. The return stroke of the piston 2 of the left hand cylinder, which takes place 85 simultaneously with the return stroke of the piston in the right hand cylinder, the poppet valve 15 being closed, compresses the air, and the operation of admitting the vapor and burning the same takes place in a like 90 manner to that of the right hand cylinder, and on its second return stroke the poppet valve 15 is opened, and the burned gases are 95 expelled through the pipe 34 into the low pressure cylinder, which acts again expansively, according to the principle of low pressure engines.

Every return stroke of the piston 18 of the low pressure cylinder expels the burned gases, through the exhaust pipe 32, into a 100 chamber 31 on the right hand side of the air tank, and then through a series of pipes 33 into a chamber 31 on the left hand side of the air tank, from whence they are expelled into the atmosphere. The expelling of the 105 burning gases through the compressed air tank serves as a means for heating the air and further compressing the same within the tank.

During this cycle of the engine, which is 110 commonly known as a four cycle, the valve plugs 12—12 reciprocate in such a manner that when the compressed air is to be admitted into one of the high pressure cylinders, the top of the plug is down below 115 the upper port, and the compressed air enters from the pipe 30 into said port and into the chamber from the top of said plug, down through the longitudinal channels in the plug, and out through the poppet valve 120 in the bottom of the chamber into the cylinder. When the exhaust gases are to be discharged from the cylinders, the plug is raised above the lower port of the chamber, as shown in its position on the left hand 125 cylinder. The poppet valve 15 being open, the burned gases pass through, up into the lower portion of the chamber, and out through the port 8 into the pipe 34, and into the upper part of the chamber of the 130

low pressure cylinder, where, the plug being in its lowered position, the gases pass through the channels in the same down into the cylinder, and act expansively, as heretofore described.

At every return stroke of the pistons 2 air is drawn in through the poppet valves 4-4, and at every forward stroke of said pistons the said air is compressed and forced 10 through the pipes 28 into the air compressor 27. Thus, in the operation of this engine, the air receives three compressions and three heatings; first, by the initial compression at the back of the pistons and the 15 heat due to said compression; secondly, the compression and heating due to the passing of the hot exhaust gases through the air tank 27; and thirdly, due to the final compression and the heat resulting from the 20 same during the return stroke of the piston when the air is admitted to the working side of the same.

This distribution of the heating and compressing of the air into three separate 25 charges is much less violent, and balances the engine in a more efficient manner than where the compression and heating takes place entirely in the cylinder. The partial compression of the air before it enters the 30 cylinder permits a greater amount of combustion to take place. As heretofore stated, the hot vapor may be admitted during the whole or a portion of the stroke, thus enabling a more constant pressure to be obtained 35 against the piston than if the same was admitted at the initial part of the stroke only, and it further enables a greater quantity of vapor to be burned during the working stroke. The greater the amount of gases 40 burned, the greater is the power of the engine during the working stroke. By admitting the vapor in a highly heated and compressed condition, the combustion of an exceedingly large amount thereof is effected 45 during the working stroke of the piston, thus greatly increasing the power and efficiency of the engine. By having the exhaust ports in the lower end of the valve chambers and below the reciprocating plugs, when the said 50 ports are open the exhaust gases pass out of the same without heating the other parts of the chamber, and at the same time, when the compressed air passes down through the channels in the plug, its temperature, being 55 much lower than that of the exhaust gases, has a tendency to cool any parts which have been heated.

Although only one form of this invention has been illustrated, it is obvious that many 60 changes might be made in the construction shown without departing from the spirit of this invention or the scope of the appended claims.

What I desire to claim and secure by Letters Patent is as follows:

1. In a compound gas engine, a pair of high pressure cylinders, one side of each operating as an air compressor, an air reservoir connected to said air compressors, means for supplying compressed air from said reservoir to said high pressure cylinders, a low pressure cylinder, and means for supplying said low pressure cylinder with the exhaust gases of the high pressure cylinders. 70

2. In a compound gas engine, a pair of high pressure cylinders, one side of each operating as an air compressor, an air reservoir connected to said air compressors, means for supplying compressed air from said reservoir to said high pressure cylinders, a low pressure cylinder, means for supplying said low pressure cylinder with exhaust gases of the high pressure cylinders, and means for utilizing the exhaust gases from the low pressure cylinder for heating the air in the 85 said reservoir. 80

3. In a compound gas engine, a pair of high pressure cylinders having pistons, one side of each cylinder operating as an air compressor, the working strokes of one high pressure piston alternating with those of the other, an air reservoir connected to said air compressors, means for supplying compressed air from said reservoir to said high pressure cylinders, a low pressure cylinder, 95 means for supplying the said low pressure cylinder with the exhaust gases from the high pressure cylinders, and means for utilizing the exhaust gases from the low pressure cylinder for heating the air in the said 100 reservoir. 90

4. In a compound gas engine, the combination with a pair of high pressure cylinders, one side of each cylinder being adapted to operate as an air compressor, of a vaporizer connected with the working side of each high pressure cylinder, a positively actuated valve for establishing connection between the working side of each high pressure cylinder and its respective vaporizer at 110 predetermined periods, an air reservoir connected to both of said air compressors, means for supplying compressed air from said reservoir to said high pressure cylinders, a low pressure cylinder, means for supplying said 115 low pressure cylinder with the exhaust gases of the high pressure cylinders, and means for utilizing the exhaust gases from the low pressure cylinder for heating the air in the 120 said reservoir. 110

5. In a compound engine, the combination with a pair of high pressure cylinders, one side of each cylinder being adapted to operate as an air compressor, of a vaporizer connected with the working side of each high 125 pressure cylinder, means for maintaining a constant pressure of the vapor in said vaporizers, and means for heating the vapor in said vaporizers, a positively actuated valve between each cylinder and its respective vap- 130

- orizer, an air reservoir connected to both of said air compressors, positively actuated valves for supplying compressed air from said reservoir to said high pressure cylinders, a low pressure cylinder, a positively actuated valve for supplying the said low pressure cylinder with the exhaust gases of the high pressure cylinders and means for utilizing the exhaust gases from the low pressure cylinder for heating the air in said reservoir.
6. In a compound gas engine, a pair of high pressure cylinders having pistons, one side of each operating as an air compressor, the working strokes of one high pressure piston alternating with those of the other, an air reservoir connected to said air compressor, means for supplying compressed air from said reservoir to said high pressure cylinders, a low pressure cylinder and means for supplying said low pressure cylinder with the exhaust gases of the high pressure cylinders.
7. In a compound gas engine, a pair of high pressure cylinders having pistons, one side of each operating as an air compressor, the working stroke of one high pressure piston being in advance of that of the other, an air reservoir connected to said air compressors, means for supplying compressed air from said reservoir to said high pressure cylinders, a low pressure cylinder, means for supplying said low pressure cylinder with the exhaust gases of the high pressure cylinders, and means for utilizing the exhaust gases from the low pressure cylinder for heating the air in the said reservoir.
8. In a compound gas engine, a pair of high pressure cylinders, and a low pressure cylinder, arranged in parallel, the low pressure cylinder being between the high pressure cylinders and one side of each high pressure cylinder operating as an air compressor, an air reservoir connected to the compressor ends of said cylinders, means for supplying compressed air from said reservoir to said high pressure cylinders, a low pressure cylinder, means for supplying said low pressure cylinder with the exhaust gases of the high pressure cylinders, and means for utilizing the exhaust gases from the low pressure cylinder for heating the air in said reservoir.
9. In a compound engine, the combination with a pair of high pressure cylinders, and a low pressure cylinder arranged in parallel, the low pressure cylinder being between the high pressure cylinders, one side of each high pressure cylinder being adapted to operate as an air compressor, of a vaporizer connected with the working side of each high pressure cylinder, means for maintaining a uniform pressure of the vapor in said vaporizer, and means for heating the vapor in said vaporizer, a positively actuated valve between each cylinder and its respective vaporizer, an air reservoir, means connecting said reservoir to both of said compressors, positively actuated valves for supplying compressed air from said reservoir to said high pressure cylinders, a positively actuated valve for supplying the said low pressure cylinder with the exhaust gases of the high pressure cylinder, and means for utilizing the exhaust gases from the low pressure cylinder for heating the air in said reservoir.
10. In a compound engine, the combination with a pair of high pressure cylinders provided with separate pistons and piston rods, one side of each cylinder being adapted to operate as an air compressor, of a vaporizer connected with each high pressure cylinder, an air reservoir connected to both of said air compressors, means for supplying compressed air from said reservoir to said high pressure cylinders, a low pressure cylinder, means for supplying said low pressure cylinder with the exhaust gases of the high pressure cylinders, and means for utilizing the exhaust gases from the low pressure cylinder for heating the air in the said reservoir.
11. In a compound gas engine, a pair of high pressure cylinders having pistons, one side of each cylinder operating as an air compressor, the working strokes of one high pressure cylinder alternating with those of the other, each cylinder being provided with a vaporizer, an air reservoir connected to said air compressors, means for supplying compressed air from said reservoir to said high pressure cylinders, a low pressure cylinder provided with a piston, the working strokes of the low pressure piston alternating with the working strokes of the high pressure pistons, means for supplying the said low pressure piston with the exhaust gases from the high pressure cylinders, and means for utilizing the exhaust gases from the low pressure cylinder for heating the air in the said reservoir.
12. In a compound gas engine, a pair of high pressure cylinders having pistons moving in unison, one side of each cylinder operating as an air compressor, the working strokes of one high pressure piston alternating with those of the other, an air reservoir connected to said air compressors, means for supplying compressed air from said reservoir to said high pressure cylinders, a low pressure cylinder, means for supplying the said low pressure cylinder with the exhaust gases from the high pressure cylinders, and means for utilizing the exhaust gases from the low pressure cylinder for heating the air in the said reservoir.
13. In a compound gas engine, a pair of high pressure cylinders having pistons moving in unison, one side of each cylinder operating as an air compressor, the working

- strokes of one high pressure piston alternating with those of the other, an air reservoir connected to said air compressors, means for supplying compressed air from said 5 reservoir to said high pressure cylinders, a low pressure cylinder having a piston the working strokes of which alternate with the working strokes of the said high pressure pistons, and means for supplying the said 10 low pressure cylinder with the exhaust gases from the high pressure cylinders.
14. In a compound gas engine, a pair of high pressure cylinders, a piston in each of said cylinders, a separate piston rod for 15 each of said pistons, said piston rods working in unison, one side of each of said cylinders acting as an air compressor, an air reservoir connected to said air compressors, means for supplying compressed air from 20 said reservoir to said high pressure cylinders, a low pressure cylinder provided with a separate piston rod the working strokes of which alternate with the working strokes of the said high pressure pistons, and means 25 for supplying said low pressure cylinder with the exhaust gases of the high pressure cylinders.
15. In a compound gas engine, a pair of high pressure cylinders provided with pistons, the same side of each of said cylinders acting as an air compressor, an air reservoir connected to said compressors, means for 30 supplying compressed air from said reservoir to said high pressure cylinders, a low pressure cylinder, a piston therefor, and means for supplying the said low pressure cylinder with the exhaust gases from said high pressure cylinders, the working strokes of said pistons being in the same direction.
16. In a compound gas engine, a pair of high pressure cylinders provided with pistons, the same side of each of said cylinders acting as an air compressor, an air reservoir connected to said compressors, means for 35 supplying compressed air from said reservoir to said high pressure cylinders, a low pressure cylinder, a piston therefor, and means for supplying the said low pressure cylinder with the exhaust gases from said high pressure cylinders, the working strokes of said pistons occurring at different periods 40 respectively and in the same direction.
17. In a compound gas engine, a pair of high pressure cylinders provided with pistons, the same side of each of said cylinders acting as an air compressor, an air reservoir connected to said compressors, means for 45 supplying compressed air from said reservoir to said high pressure cylinders, a low pressure cylinder, a piston therefor, and means for supplying the said low pressure cylinder with the exhaust gases of the high pressure cylinder, and means for utilizing the exhaust gases from the low pressure cylinder for heating the air in said 50 reservoir.
18. In a compound gas engine, the combination with a high pressure cylinder, one side of which is adapted to operate as an air compressor, of an air reservoir connected to said air compressor, means for supplying compressed air from said reservoir to the other side of said high pressure cylinder, a low pressure cylinder, means for supplying said low pressure cylinder with the exhaust gases of the high pressure cylinder, and means for utilizing the exhaust gases from the low pressure cylinder for heating the air in said reservoir.
19. In a compound gas engine, the combination with a high pressure cylinder, one side of which acts as an air compressor, of a vaporizer connected with the working side of said cylinder, a positively actuated valve for establishing communication between the cylinder and its vaporizer at predetermined periods, an air reservoir connected to said compressor, means for supplying compressed air from said reservoir to the working side of said cylinder, a low pressure cylinder, means for supplying said low pressure cylinder with the exhaust gases of the high pressure cylinder, and means for utilizing the exhaust gases from the low pressure cylinder for heating the air in the said reservoir.
20. In a compound gas engine, the combination with a high pressure cylinder, one side of which operates as an air compressor, of a vaporizer communicating with the other side of said cylinder, means for maintaining a constant pressure of the vapor in said vaporizer, means for heating the vapor in said vaporizer, a positively actuated valve between said cylinder and its vaporizer, an air reservoir connected to said air compressor, a positively actuated valve for supplying compressed air from said reservoir to said high pressure cylinder, a positively actuated valve for supplying the said low pressure cylinder with the exhaust gases of the high pressure cylinder, and means for utilizing the exhaust gases from the low pressure cylinder for heating the air in said reservoir.
- In witness whereof, I have hereunto set my hand this 29th day of December, A. D. 1905.
